ABSTRACT: An ignition system of a capacitor discharging type for internal combustion engines having a DC-DC converter, a discharging capacitor, an ignition coil and a silicon-controlled rectifier. In the system, a differentiation circuit, a waveform shaping circuit and a switching element are additionally provided so that the switching element interposed in the base-emitter circuit of an oscillation transistor in the DC-DC converter is actuated by the output pulse from the waveform shaping circuit to cease the operation of the DC-DC converter for a period of time corresponding to the duration of the pulse.

IGNITION SYSTEM FOR INTERNAL COMBUSTION ENGINES

BACKGROUND OF THE INVENTION

1. Field of the Invention

This invention relates to improvements in capacitor discharging type of ignition systems for internal combustion engines.

2. Description of the Prior Art

Operation of prior art ignition systems of the capacitor discharging type has been such that the voltage of a storage battery is stepped up by means of a DC-DC converter so as to charge a discharging capacitor by the stepped-up voltage, the charge stored in the discharging capacitor is discharged through a primary winding of a ignition coil and a silicon controlled rectifier at the proper ignition time of the engine, and a high voltage thereby induced in a secondary winding of the ignition coil is applied to a spark plug for generating a spark across the spark gap of the spark plug.

However, the prior art ignition systems described above have been defective in that, as soon as the discharging capacitor completes its discharge, the DC-DC converter starts to charge the discharging capacitor to prepare for the next ignition and thus the silicon-controlled rectifier cannot be properly turned off. **SUMMARY OF THE INVENTION**

In an attempt to overcome the above defect encountered with the prior art ignition systems, it is a primary object of the present invention to provide an ignition system of the capacitor discharging type for internal combustion engines having a DC-DC converter, a discharging capacitor charged by the output from said DC-DC converter, an ignition coil interposed in the discharge circuit of said discharging capacitor, and a silicon-controlled rectifier for opening and closing said discharge circuit, said ignition system comprising a differentiation circuit for detecting a variation in the voltage across said discharging capacitor during the discharging period of the latter, a waveform shaping circuit for shaping the output from said differentiation circuit into a rectangular waveform, and a switching element interposed in said DC-DC converter, said switching element being actuated by the output pulse delivered from said waveform shaping circuit so as to cease the operation of said DC-DC converter for a period of time which corresponds to the duration of the pulse, whereby said silicon-controlled rectifier completes its turned-off state during the period of time in which said DC-DC converter is held in its nonoperative state.

BRIEF DESCRIPTION OF THE DRAWING

FIG. 1 is an electrical connection diagram of an embodiment of the ignition system for internal combustion engines according to the present invention;

FIG. 2 is a block diagram showing schematically the structure of the system of the present invention;

FIG. 3 is a graphic representation of electrical characteristics for illustrating the operation of the system according to the present invention.

DESCRIPTION OF THE PREFERRED EMBODIMENT

Referring to **FIG. 1**, the ignition system according to the present invention comprises a storage battery 1 which is a power source, a main switch 2, a step-up transformer 3 having a primary winding 4, a secondary winding 5 and a feedback winding 6, an oscillation transistor 7 for performing a blocking oscillation function, a resistor 8 and a capacitor 9 constituting a feedback circuit, a biasing resistor 10 for the transistor 7, a high-voltage pulse absorbing capacitor 11, a rectifying diode 12 and a discharging capacitor 13. An ignition coil 14 has a primary winding 15 and a secondary winding 16, and a spark plug 17 is connected to the secondary winding 16 of the ignition coil 14. A silicon-controlled rectifier 18 interrupts the primary current in the ignition coil 14. The primary winding 15

of the ignition coil 14 has one end thereof connected to one terminal of the discharging capacitor 13 and the other end thereof is connected to the anode of the silicon-controlled rectifier 18, while the cathode of the silicon-controlled rectifier 18 is connected to the other terminal of the discharging capacitor 13 to constitute a discharge path for the discharging capacitor 13. A diode 19 supplies to the primary winding 15 a current which is in reverse direction to the current passing through the silicon-controlled rectifier 18, and a choke coil 20 which regulates the period of time of flow of the reverse current. A capacitor 21 constitutes together with resistors 22 and 23 a differentiation circuit which detects a variation in the voltage appearing across the discharging capacitor 13. The ignition system further comprises a biasing resistor 24, a reverse-voltage preventive diode 25, a differentiated pulse-amplifying transistor 26, a load resistor 27 for the transistor 26, a capacitor 28 for transmitting to the next stage the output pulse appearing at the collector of the transistor 26, resistors 29 and 30 for dividing the voltage appearing across the discharging capacitor 13, a Zener diode 31, a biasing resistor 32, an amplifying transistor 33, a load resistor 34 for the transistor 33, a coupling resistor 35, a biasing resistor 36, a phase inversion transistor 37, and a switching element 39 in the form of a transistor which is provided to short circuit the base and emitter of the oscillation transistor 7. The switching element 39 may be a silicon-controlled rectifier in lieu of a transistor.

FIG. 2 is a block diagram of the system according to the present invention having a structure as shown in **FIG. 1**. Operation of the system according to the present invention will be described with reference to **FIG. 2**. A DC-DC converter 40 constituted by the circuit elements 3 to 12 is operative to oscillate, step up, and rectify the voltage of the storage battery 1 so as to convert such voltage into a high DC voltage which is then stored in the discharging capacitor 13. The distributor points 100 are opened at the proper time of engine ignition so that the timing circuit is operated to supply a signal to the silicon-controlled rectifier 18. When the signal is supplied to the gate of the silicon-controlled rectifier 18 at the proper time of ignition of the fuel-air mixture in the engine and the silicon-controlled rectifier 18 is thereby turned on, the charge stored in the discharging capacitor 13 is discharged through the primary controlled rectifier 18. At this instant, a high voltage is induced in the secondary winding 16 of the ignition coil 14 and is applied to the spark plug 17 to make a spark jump across the gap of the spark plug 17. In the meantime, a differentiation circuit 41 constituted by the circuit elements 21 and 23 detects a variation in the voltage across the discharging capacitor 13 during the discharge of the latter. A waveform shaping circuit 42 constituted by the circuit elements 24 to 28 delivers a pulse of rectangular waveform when it receives such a voltage variation. The pulse is applied to the base of the transistor 39 to urge the transistor 39 to its conducting state. As a result, a short circuit is effected between the base and emitter of the oscillation transistor 7 so that the DC-DC converter 40 ceases its operation during the period of time corresponding to the pulse duration of the pulse.

The above operation will be described in more detail with reference to **FIG. 3**. In **FIG. 3(a)**, the horizontal axis represents time t and the vertical axis represents voltage V_c across the discharging capacitor 13. In **FIG. 3b**, the horizontal axis represents time t and the vertical axis represents pulse voltage V_p . Up to time $t=t_p$ at which the pulse coming from the waveform shaping circuit 42 disappears, the DC-DC converter 40 is held in its nonoperative state and the voltage V_c across the discharging capacitor 13 is kept constant. In this connection, it will be noted that the value of the voltage V_c across the discharging capacitor 13 is kept constant from time t_1 to t_p of the fact that the DC-DC converter 40 is not in operation. When the silicon-controlled rectifier 18 is turned on, the charge stored in the discharging capacitor 13 is completely discharged through the primary winding 15 of the ignition coil 14 and through the silicon-controlled rectifier 18. After the

charge in the discharging capacitor 13 reaches a maximum value of polarity opposite to the polarity initially charged therein, the charge of opposite polarity is discharged by way of the following two discharge circuits. The first discharge circuit includes the choke coil 20, the diode 19 and the primary winding 15 of the ignition coil 14. Since the first discharge circuit has a very low combined impedance, the greater portion of the charge of inverted polarity in the discharging capacitor 13 is discharged through the first discharge circuit. The second discharge circuit includes the secondary winding 5 of the step-up transformer 3 and the diode 12. This second discharge circuit serves to charge the discharging capacitor 13 by the output from the DC-DC converter 40. If the DC-DC converter is still in operation even after the charge in the discharging capacitor has been reversed, the output from the DC-DC converter 40 would positively charge the discharging capacitor 13 to cancel out the charge of inverted polarity in the discharging capacitor 13 with the result that a reverse bias voltage which is sufficient to turn off the silicon-controlled rectifier 18 would not be obtained. Further, the current output flowing from the DC-DC converter 40 through the diode 12 is a forward current for the silicon-controlled rectifier 18 and such a current would have a substantial effect on the failure of the silicon-controlled rectifier 18 to turn off. However, according to the present invention, failure to turn off of the silicon-controlled rectifier 18 by the above phenomenon does never occur for the following reason. The differentiation circuit 41 detects a variation in the voltage across the discharging capacitor 13 due to the initial discharge and a pulse of a rectangular waveform is thereby delivered from the waveform shaping circuit 42 to urge the transistor 39 to conduct, thereby stopping the operation of the DC-DC converter 40. If the DC-DC converter 40 is held in its nonoperative state ranges from $t=t_1$ at which time the charge in the discharging capacitor 13 after polarity inversion has been turned positive again to $t=t_p$, at which time the pulse of the rectangular waveform disappears, the voltage V_c across the discharging capacitor 13 is held constant between time $t=t_1$ and time $t=t_p$. Thus, up to time $t=t_1$ at which the discharging capacitor 13 is discharged initially is charged to positive polarity again after taking a maximum value of opposite polarity, voltage is applied to the silicon-controlled rectifier 18 in a direction in which a reverse current flows. It will therefore be understood that the silicon-controlled rectifier 18 can be positively turned off when the operation of the DC-DC converter 40 is carried out in the manner described above. Thus, the voltage V_c across the discharging capacitor 13 is kept constant during the time period represented between t_1 to t_p . In this manner, the DC-DC converter 40 is held in its nonoperative state for an additional period of time beyond time $t=t_1$ at which the current tends to flow in the forward direction of the silicon-controlled rectifier 18. However, at time $t=t_1$, the silicon-controlled rectifier 18 has already been turned off and would not be turned on again until an ignition signal is supplied to the gate thereof. In other words, since the DC-DC converter 40 is held in its nonoperative state, no current flows from the DC-DC converter 40 through the silicon-controlled rectifier 18 up to time $t=t_1$ and thus the silicon-controlled rectifier 18 is positively turned off.

A constant-voltage control circuit 43 constituted by the circuit elements 29 to 38 operates in such a manner that the resistors 29 and 30 and the Zener diode 31 therein detect the voltage across the discharging capacitor 13 so that the transistor 39 is urged to conduct to forcedly cease the operation of the DC-DC converter 40 when the voltage across the discharging capacitor 13 exceeds a predetermined setting which is determined by the resistors 29 and 30 and the Zener diode 31. Thus, the voltage across the discharging capacitor 13 can be controlled at a constant voltage which is sufficient to make a spark jump across the spark gap of the spark plug 17.

From the foregoing description, it will be understood that the present invention provides an ignition system of the capacitor discharging type for internal combustion engines

having a DC-DC converter, a discharging capacitor charged by the output from said DC-DC converter, an ignition coil interposed in the discharge circuit of said discharging capacitor, and a silicon-controlled rectifier for opening and closing said discharge circuit, said ignition system comprising a differentiation circuit for detecting a variation in the voltage across said discharging capacitor during the discharging period of the latter, a waveform shaping circuit for shaping the output from said differentiation circuit into rectangular waveform, and a switching element interposed in the base-emitter circuit of an oscillation transistor in said DC-DC converter, said switch element being actuated by the output pulse delivered from said waveform shaping circuit so as to cease the operation of said DC-DC converter for a period of time which corresponds to the duration of the pulse, whereby said silicon-controlled rectifier completes its turned-off state during the period of time in which said DC-DC converter is held in its nonoperative state.

What is claimed is:

1. An improved ignition system of the capacitor discharging type for internal combustion engines including a DC-DC converter having an oscillator therein, a discharging capacitor which is charged by an output of said DC-DC converter, an ignition coil disposed in a discharging circuit of said discharging capacitor and a silicon-controlled rectifier connected in series with said discharging capacitor and a primary winding of said ignition coil, wherein said rectifier is more effectively switched "off" at the completion of a discharge cycle, said improved system comprising:

a differentiation circuit for detecting a variation in a voltage across said discharging capacitor during a discharging period of said discharging capacitor,

a waveform shaping circuit for shaping an output of said differentiation circuit into a rectangular waveform, and a switching element disposed in a circuit of said oscillator in said DC-DC converter, said switching element being actuatable by said rectangular waveform for stopping the operation of said oscillator thereby substantially eliminating said output of said DC-DC converter for a period of time corresponding to the duration of said rectangular waveform thus insuring that said rectifier may be positively turned off after said discharging period.

2. An ignition system as in claim 1 wherein said DC-DC converter comprises:

a transformer having a primary winding, a secondary winding and a feedback winding, and a blocking oscillator circuit including a transistor and a parallel connection of a resistor and a capacitor.

3. An ignition system as in claim 1 wherein a series connection of an inductance for contributing to the extinguishment of said silicon-controlled rectifier and a reversed current preventative diode is connected in parallel with said silicon-controlled rectifier.

4. An ignition system as in claim 1 wherein said waveform shaping circuit and said switching element are connected with each other via capacitor and said ignition system further comprises a constant-voltage control circuit which is operated by a voltage across terminals of said discharging circuit for generating a signal voltage and for energizing said switching element when said voltage exceeds a predetermined value.

5. An ignition system as in claim 2 wherein said switching element comprises a transistor for establishing an effective short circuit between base and emitter electrodes of transistor in said oscillator.

6. An improvement for use in a capacitor discharge ignition system comprising a controlled rectifier in capacitor discharge circuit and a DC-DC converter which includes an oscillator means, said improvement comprising:

differentiation means connected to said discharge circuit for detecting a discharge period signified by a rapid voltage variation therein,

waveform shaping means connected to said differentiation means for producing an output signal in response to the detection of said discharge period, and

switch means connected from said waveform shaping means to said DC-DC converter for causing said oscillator means to be inoperative in response to said output signal

and for thereby substantially eliminating a DC output of said DC-DC converter and causing substantial cessation of current flow through said controlled rectifier.
